(57) **CLAIM**

The ornamental design for the circular plastic/metal composite stress plate with fastener, as shown and described.

DESCRIPTION

FIG. 1 is a top perspective view of the circular plastic/metal composite stress plate with fastener of the present design; FIG. 2 is a side elevational view of the design, all other sides being identical thereto; FIG. 3 is a top plan view thereof; and, FIG. 4 is a bottom perspective view thereof. The broken lines shown on the drawings are for illustrative purposes only and form no part of the claimed design.
